COATING APPARATUS

Yves A. Bouget, West Orange, N. J., assignor to
Western Electric Company, Incorporated, New
York, N. Y., a corporation of New York

Application July 3, 1943, Serial No. 493,337

16 Claims. (Cl. 91—12.5)

This invention relates to coating apparatus, and more particularly to apparatus for tinning electrical conductors.

In tinning electrical conductors by passing them into and out of an open bath of the molten tin, there exists a thickness of dross upon the bath through which the conductors must travel not only in entering but in leaving the bath. Furthermore, in causing the conductors to travel into the bath they may be disturbed not only by the frictional contact with elements necessary for the direction of their travel but are further disturbed by having to be bent about such elements during the coating operation. It has been found necessary to eliminate the presence of dross through which the conductors to be tinned must pass and to provide only uncontaminated molten tin for the coating of the conductors. Furthermore, to provide a more uniform coating and to make possible satisfactory coating of the conductors during more rapid advancement thereof, it has been found that such is possible by moving the conductors in a straight path to, through and beyond the coating material.

An object of the invention is to provide an efficient apparatus for supplying uncontaminated coating material to a strand during the advancement of the strand in a given plane.

With this and other objects in view, the invention comprises a coating apparatus having a coating unit with a track therein for the advancement of a strand therethrough and compartments therein sealed against the atmosphere for supplying coating material to the strand.

Other objects and advantages will be apparent from the following detailed description when considered in conjunction with the accompanying drawings, wherein

Fig. 1 is a top plan view of the apparatus, a portion thereof being broken away;

Fig. 2 is a vertical sectional view taken substantially along the line 2—2 of Fig. 1;

Fig. 3 is a side elevational view of the apparatus taken substantially along the line 3—3 of Fig. 1, with portions thereof being broken away to show the internal structure thereof;

Fig. 4 is an enlarged fragmentary sectional view taken along the line 4—4 of Fig. 3;

Fig. 5 is a fragmentary sectional view taken along the line 5—5 of Fig. 4;

Fig. 6 is a fragmentary sectional view taken along the line 6—6 of Fig. 5, and

Fig. 7 is a side elevational view of one of the coating units of the apparatus.

Referring now to the drawings, attention is

first directed to Figs. 1, 2 and 3, wherein there is illustrated a housing 10 having a depressed central portion 11 terminating short of the ends of the housing, providing openings 12 and 14. 5 The central portion 11 is recessed to receive and support a head plate 15, which is of the width shown in Fig. 2 and extends the full length of the central portion 11 (Fig. 1). The head plate 15 in the present embodiment is of a sufficient width to support six coating units 16 to 21 inclusive, located thereon by pins 23 disposed at the position shown in Fig. 1 in the head plate 15, and receivable in the apertures shown, disposed in the ends of the units. Thus the units may be 10 accurately located in their respective adjacent parallel positions on the head plate.

The units 16 to 21 inclusive are identical in structure and a description of one will apply equally well to all of the units. In the end portion 20 of each unit (Fig. 4 showing the unit 17), a plurality of compartments is formed by baffles 25 extending angularly from a path for the strand or conductor 26, to serve in controlling the direction of flow of the coating material. The baffles 25 and the parallel side walls of the bottom portion of the unit have their surfaces lying in a common plane to rest upon the head plate 15 and, through the application of suitable pressure, form a fluid seal therebetween. The compartments formed in the unit 17 by the baffles 25 in the side walls are in pairs identified by reference numerals 27 to 35 inclusive. In actual structure there may be more compartments disposed upon either side of the central pair of compartments 31, depending upon the desired length of the units. The compartments 31 are triangular in general contour and have pins 37 fixedly disposed in apertures therein for actuating valves hereinafter described. The triangular compartments 31 are also provided with outlets 38 at their vertices for the passage of a fluid material, such as molten tin alloy, from the compartments to the strand 26. The compartments at the left, namely compartments 27 to 30 inclusive, are 30 formed by their baffles 25 to provide pockets tending to check the back flow of the material against the travel of the strand and to provide storing spaces for excess quantities of the material from which the strand is to be coated. The compartments at the right of the center, namely compartments 32 to 35 inclusive, lead toward the direction of travel of the strand, so as to aid in the feeding of the material thereto. The inner ends of the baffles are so spaced that 35 passages are provided therebetween in an outer

aligned path to aid in guiding the strand in a straight path. These ends of the baffles may also be rounded sufficiently for the smooth passage of the strand therebetween, without interfering with the application of the coating material thereto but serving as wiping dies therefor. It will also be noted, by viewing Fig. 5, which illustrates a cross-sectional view of the unit 17, that the top walls of the compartments taper upwardly so that the greatest depths of the compartments are at the path of the strand to encourage the material to remain adjacent the path, yet provide additional space for the excess quantities of the material. Also, a central rib portion 40 of the unit extends the full length thereof, as shown in Figs. 1, 3 and 7, this rib being provided with notches 41 at the ends thereof to receive the strand during the threading thereof and the conditioning of the apparatus for use.

Referring now to Figs. 5 and 6, it will be noted that the head plate 15 is apertured at 44 to receive not only the valve actuating pins 37 but ball valves 45. Valve seats 46 in the adjacent portions of the central portion 11 complete the cavities for the valves 45. Passageways 47, extending angularly therefrom, provide communication between valve cavities and a main supply passageway 48. The main supply passageway for the unit 17 and those for the other units are vertically disposed in projections 49 integral with the central portion 11 (Fig. 2) and extends a given distance therebeneath.

In addition to the pins 23 receivable in the unit apertures, means is provided to individually hold the separate units in place upon the head plate under sufficient force to form a seal therebetween. This means includes a plurality of cams 50, each rotatably mounted upon a stationary shaft 51, the ends of the latter being disposed in and fixed to brackets 52 integral with or mounted upon the housing 10. Suitable spacers 53 are disposed between the cams 50 for the location of the latter above the rib portions of their respective units. Handles 54, fixed to the cams 50, provide means for the individual actuation of the various cams.

A container 55 for the coating material, namely molten tin alloy, is disposed in the housing and has an outwardly flared integral flange 56, apertured at the corners thereof, to movably receive threaded supports 57. Lower heads 58 of the supports 57, aided by washers 59, support springs 62, which in turn support the container 55 at the adjacent portions of the flange 56. A central portion of each of the supports 57 is threaded as at 64, and is disposed in a threaded portion 65 of the housing 10. A sprocket 66 is disposed upon and fixed to each support 57, these sprockets being operatively connected to each other by a continuous chain 68. Suitable means, such as a crank lever 69, is mounted upon the outer end of one of the supports for the rotation thereof, and through the sprocket and chain connections, to cause simultaneous and like rotation of all of the supports.

Suitable heating means or units 70 and 71 are provided to heat the material in the container 55, the heating means 70 extending spirally about the vertical walls of the container while the heating means 71 is positioned across the bottom thereof. The container 55 is divided into an outer chamber 73 and an inner chamber 74 by an expandable and contractable unit 75 cylindrical in general contour and of the cross-sectional contour shown in Fig. 2. The unit 75 surrounds the

projections 49 so that the passageways 48 therein will be fed material only from the inner chamber 74. A passageway 77 provides communication between the chambers 73 and 74, this passageway being under the control of a valve 78 threadedly supported at 79, guided at 80 and provided with a hand wheel 81, or other suitable means for its actuation, disposed upon the outer end thereof and positioned externally of the housing 10.

Upon considering the operation of the apparatus, let it be assumed that none of the wires or strands 26 has been threaded and that all of the units 16 to 21 inclusive have been removed from the head plate 15. Let it further be assumed that the container 55 is in its uppermost position with the bottom wall thereof closely adjacent the lower ends of the projections 49 (Fig. 2) and that the valve 78 has been opened. With the material in the chamber 73 in a liquid state, through the actuation of the hand lever 69 to cause simultaneous rotation of the supports 57 through the sprocket and chain connections, the container 55 may be lowered, expanding the bellows-like unit 75 until the container is in its lowermost position adjacent the bottom of the housing 10. During this interval of travel of the container which is brought about by the weight thereof and the contents of the material therein, the valve 78 is open, but the passageways 47 (Figs. 5 and 6) are closed by the valves 45. It is also important that the valves 45 seal the chamber 74 against the admission of air. As an added protection against the admission of air, a metallic member of sufficient length to extend across the valves 45, that is their outlets through the head plate 15, and of a sufficient height to be held down by any desired number of the cams 50, may at this time be employed if so desired. However, the valves 45 will under such circumstances come to rest upon their seats 46, to seal the passageways 47 against the admission of air. The next step of the operation is to close the valve 78 through the aid of the hand wheel 81, to close communication between the chambers 73 and 74.

At this time various wires or strands 26 may be threaded through their respective units. In threading the wires, a suitable length of each wire is extended past the exit end of its respective unit and positioned in the path between the ends of the baffles 25, drawn taut and hooked about the ends of the units in the notches 41, as illustrated in Fig. 7. As each wire is threaded in its unit, the unit thereof is disposed in its respective position over the pins 23 and locked in place by its respective cam 50, the pins 37 of the unit forcing their respective valves 45 (Fig. 6) open, to open communication between the chamber 74 and the compartments in the unit. This same series of steps is followed for the threading of each wire in its respective unit. After each wire is threaded and the unit thereof secured in place, the wire may be unhooked from the unit and moved into a straight line for advancement through the unit by any suitable means (not shown).

At this time the operator actuates the crank lever 69 (Figs. 1 and 2) to cause simultaneous movement of the supports 57, tending to move the container 55 upwardly. The supports 57 are moved upwardly their complete or desired distances, and although the container 55 cannot follow immediately due to the fact that the chamber 74 is filled with material, a desired force is applied to the container to cause it to continue

its upward movement as the material from the chamber 14 passes therefrom through the various passageways 48 toward their respective units. The valves 45 having been opened and held in this position by the pins 37, the molten material is forced into the compartments 31 of each unit and through the passageways 38 toward the wire or strand to be coated. The coating material is thus advanced to the units in greater quantities than can be received by the strands, but these excess quantities are receivable in the compartments upon each side of the central compartments 31, extending the length of the application portion of each unit, that is the portion where the coating material is applied to the strand, so that the strand may be thoroughly coated with the material. Portions of the coating material move in a direction opposite that of the advancement of the wire or strand, the compartments 21 to 30 inclusive, however, being formed to check the passage of the material in this direction, providing pockets for retaining the material. These pockets are formed by baffles 25, which also provide spaced edges limiting the passageway to a size sufficient for the passage of the strand and to limit the escapement of the material. The various groups of arrows in the illustration shown in Fig. 4 demonstrate the possible passage of the coating material, illustrating that in the compartments back of the initial points of application of the material at the passageways 38, the material is directed into the pockets and away from the outlets, whereas in the compartments 32 to 35 inclusive the contours of the baffles direct the material toward the outlets and toward the strand or wire to be coated. It will, therefore, be apparent that each coating unit is capable of supplying coating material to the wire for a considerable length of the wire simultaneously in quantities in excess of that necessary, yet maintain these quantities of coating material free of contact with the atmosphere, thus in a purified state and in the desired molten condition for application to subsequent portions of the strand. Furthermore, the strands in passing through the units, travel in direct uninterrupted paths free of distortion and through quantities of coating material maintained free of undesired particles and free of air throughout the coating operation.

It is preferred that strands or wires of equal length be coated simultaneously, so that the threading operation may be performed all at one time. However, it may be possible that the strands or wires may be of various lengths and in such instances it is possible to remove any one of the units 16 to 21 inclusive without disturbing the continued coating operation performed by the other units during the re-threading of the first mentioned unit. By removing the empty unit, the valves 45 thereof are closed upon the removal of the pins 31, to seal the passageways 48 linked therewith against the escapement of liquid from the chamber 14. The wire may be readily threaded through the unit and the unit against disposed in position and locked in place. It requires but a few seconds to thread each unit and to continue its function, the coating of the strand.

It will be apparent that there are not heating elements immediately adjacent the units 16 to 21 inclusive. Such heating elements are not necessary in view of the fact that the units and the head plate 15 are disposed within the heating range of the elements 10 and 11, the mate-

rial being maintained in a fluid state through the heat from these heating elements. Furthermore, the function of the units in providing a series of compartments upon each side of the entrance or initial application points (38) for the material, causes pre-heating of the strands by the material to assure uniform coating operations.

Although specific improvements of the invention have been shown and described, it will be understood that they are but illustrative and that various modifications may be made therein without departing from the scope and spirit of this invention as defined by the appended claims.

What is claimed is:

15. An apparatus for coating strands comprising a coating unit formed for the advancement of a strand therethrough and having an inlet for a coating material for coating the strand, a supply of the coating material, an expandable and contractable chamber having a flexible wall, means affording communication between the chamber and the said inlet, and means actuatable to alternately expand and contract the chamber to respectively draw a quantity of the material from the supply into the chamber and force material from the chamber through inlet into the unit.
20. An apparatus for coating strands comprising a coating unit formed for the advancement of a strand therethrough and having an inlet for a coating material for coating the strand, a supply of the coating material, an expandable and contractable chamber having a flexible wall, a valve actuatable to control communication between the supply and the chamber, and means actuatable to alternately expand and contract the chamber to respectively draw a quantity of the material from the supply into the chamber and force material from the chamber through inlet into the unit.
25. An apparatus for coating strands comprising a coating unit formed for the advancement of a strand therethrough and having an inlet for a coating material for coating the strand, a supply of the coating material, an expandable and contractable chamber having a flexible wall, a valve actuatable to control communication between the supply and the chamber, and means actuatable to alternately expand and contract the chamber to respectively draw a quantity of the material from the supply into the chamber and force material from the chamber through inlet into the unit.
30. An apparatus for coating strands comprising a coating unit formed for the advancement of a strand therethrough and having an inlet for a coating material for coating the strand, a supply of the coating material, an expandable and contractable chamber having a flexible wall, means affording communication between the chamber and the said inlet, means actuatable to expand the chamber to draw material from the supply into the chamber, means actuatable to afford communication between the chamber and the supply, and means to apply a force to the chamber urging contraction thereof to force the material therein through the said communicating means, the inlet and into the unit about the strand.
35. An apparatus for coating strands comprising a coating unit formed for the advancement of a strand therethrough and having an inlet for a coating material for coating the strand, a supply of the coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
40. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
45. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
50. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
55. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
60. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
65. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
70. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.
75. An apparatus for coating strands comprising a coating unit formed for the advancement of a strand therethrough and having an inlet for a coating material for coating the strand, a container for a supply of coating material, an expandable and contractable chamber disposed in the container and fixed thereto, means to cause lowering of the container to cause expansion of the chamber, means actuatable to open communication between the container and the chamber for the filling of the chamber with the material, and means affording communication between the chamber and the said inlet.

lowering of the container to cause expansion of the chamber, means actuatable to open communication between the container and the chamber for the filling of the chamber with the material, and a valve actuatable to control communication between the chamber and the said inlet.

6. An apparatus for coating strands comprising a coating unit formed for the advancement of a strand therethrough and having an inlet for a coating material for coating the strand, a container for a supply of coating material, an expansible and contractable chamber disposed in the container and fixed thereto, means to cause lowering of the container to cause expansion of the chamber, means cooperating with the last mentioned means to apply a force to the container to move it upwardly and contract the chamber, and means actuatable to open communication between the container and the chamber for the drawing of the material into the chamber from the container and to close communication therebetween.

7. An apparatus for coating strands comprising a coating unit formed for the advancement of a strand therethrough and having an inlet for a coating material for coating the strand, a container for a supply of coating material, an expansible and contractable chamber disposed in the container and fixed thereto, means to cause lowering of the container to cause expansion of the chamber, means cooperating with the last mentioned means to apply a force to the container to move it upwardly and contract the chamber, and means actuatable to open communication between the container and the chamber for the drawing of the material thereinto from the bottom of the container and to close communication therebetween.

8. An apparatus for coating strands comprising a coating unit formed for the advancement of a strand therethrough and having an inlet for a coating material for coating the strand, a container for a supply of coating material, an expansible and contractable chamber disposed in the container and fixed thereto, means to cause lowering of the container to cause expansion of the chamber, means cooperating with the last mentioned means to apply a force to the container to move it upwardly and contract the chamber, means actuatable to open communication between the container and the chamber for the drawing of the material thereinto from the container and to close communication therebetween, and means affording communication between the chamber and the said inlet.

9. An apparatus for coating strands comprising a support, adjacent to which a strand is advanced longitudinally, having an outlet therein for a coating material, means to force the coating material through the outlet and onto the support, and a unit having aligned passageways therein for guiding the strand and recesses cooperating with the support to form compartments for the material to surround the strand.

10. An apparatus for coating strands comprising a support, adjacent to which a strand is advanced longitudinally, having an outlet therein for a coating material, a valve adapted to close the outlet, a unit disposed on the support adapted to guide the strand and cooperating with the

support to direct the coating material thereto, and means carried by the unit to move the valve into open position.

11. An apparatus for coating strands comprising a support, adjacent to which a strand is advanced longitudinally, having an outlet therein for a coating material, a valve adapted to close the outlet, a unit disposed on the support adapted to guide the strand and cooperating with the support to direct the coating material thereto, and means carried by the unit to move the valve into open position when the unit is disposed on the support.

12. An apparatus for coating strands comprising a support having an outlet therein for a coating material, means to force the coating material through the outlet and onto the support, a unit having passageways therein to receive a strand and a recess to cooperate with the support to form a compartment for the material to surround the strand, and means carried by the unit to hold the strand in the passageways during positioning of the unit on the support.

13. An apparatus for coating strands comprising a support having an outlet therein for a coating material, means to force the coating material through the outlet and onto the support, a unit having passageways therein to receive a strand and a recess to cooperate with the support to form a compartment for the material to surround the strand, means carried by the unit to hold the strand in the passageways during positioning of the unit on the support, and means to removably secure the unit in place on the support.

14. An apparatus for coating strands comprising a support having an outlet therein for a coating material, means to force the coating material through the outlet and onto the support, a unit having passageways therein to receive a strand and a recess to cooperate with the support to form a compartment for the material to surround the strand, means carried by the unit to hold the strand in the passageways during positioning of the unit on the support, and means to removably hold the unit on the support to cause forming of a fluid tight seal therebetween.

15. An apparatus for coating strands comprising a support, adjacent to which a strand is advanced longitudinally, having an outlet therein for a coating material, means to force the coating material through the outlet and onto the support, a unit having strand guiding passageways therein and spaced recesses to cooperate with the support to form compartments longitudinally of the advancing strand, and means to removably secure the unit to the support.

16. An apparatus for coating strands comprising a support, adjacent to which a strand is advanced longitudinally, having an outlet therein for a coating material, means to force the coating material through the outlet and onto the support, a unit having strand guiding passageways therein and spaced recesses to cooperate with the support to form compartments longitudinally of the advancing strand, the passageways affording communication between the compartments, and means to removably secure the unit to the support.

YVES A. BOUGET.
